INDOOR WALL BOOTH

George H. Phillips, Jr., 802 Highland Terrace NE,
Atlanta, Ga.

Filed Aug. 4, 1960, Ser. No. 61,629

Term of patent 14 years

(Cl. D13—1)

FIG. 1

FIG. 2

FIG. 3

FIG. 1, is a view in perspective of an indoor wall booth embodying the instant design;

FIG. 2, is a cross-sectional view taken along the line 2—2 of FIG. 3; and

FIG. 3, is a top view.

This application is a continuation-in-part of copending application Serial No. D-56,274, filed June 8, 1959, for a telephone booth by this same applicant and now abandoned.

It is to be understood that the perforations, partially shown in FIGS. 1 and 2, are continuous throughout the inner vertical walls of the booth.

I claim:

The ornamental for an indoor wall booth, as shown and described.
